US00D604238S

(12) **United States Design Patent**
Engel et al.

(10) **Patent No.:** US D604,238 S
(45) **Date of Patent:** ** Nov. 17, 2009

(54) **INVERTER**

(75) Inventors: **Bernd Engel**, Wolfenbüttel (DE);
Andreas Donth, Edermündel (DE)

(73) Assignee: **SMA Solar Technology AG.**, Niestetal
(DE)

(**) Term: **14 Years**

(21) Appl. No.: **29/312,793**

(22) Filed: **Nov. 12, 2008**

(30) **Foreign Application Priority Data**

May 19, 2008 (EM) 000937578

(51) **LOC (9) Cl.** 13-02

(52) **U.S. Cl.** D13/110

(58) **Field of Classification Search** D13/110,
D13/123, 184, 199; 337/186; 361/600, 601,
361/730; 363/141, 142

See application file for complete search history.

(57) **CLAIM**

The ornamental design for an inverter, as shown and described.

DESCRIPTION

FIG. 1 is a perspective view of an inverter showing our new design;

FIG. 2 is a top plan view thereof;

FIG. 3 is a left side view thereof;

FIG. 4 is a bottom plan view thereof;

FIG. 5 is a front elevation view thereof; and,

FIG. 6 is a rear elevation view thereof.

The broken lines shown represent unclaimed subject matter and form no part of the claimed design.

1 Claim, 6 Drawing Sheets

FIG. 1

FIG. 2

FIG. 3

FIG. 4

FIG. 5

FIG. 6
